CHECK HOLDER

August Zamborelli, Sopris, Colo.

Application October 21, 1936, Serial No. 106,876

1 Claim. (Cl. 40—15)

This invention appertains to new and useful improvements in holders or hooks for checks such as are used by miners to identify their pit cars in coal mines.

5 The principal object of the present invention is to provide a check holder or hook which has the safety feature of preventing the check from becoming accidentally displaced.

Another important object of the invention is 10 to provide a holder of the character described which is positive acting and not susceptible to the ready development of defects.

15 These and various other important objects and advantages of the invention will become apparent to the reader of the following specification.

In the drawings:

Figure 1 represents a side elevational view of the holder in supported position.

20 Figure 2 is a vertical sectional view taken substantially on line 2—2 of Figure 1.

Figure 3 represents a vertical sectional view taken substantially on line 3—3 of Figure 1.

25 Figure 4 represents a perspective view of the detent.

Figure 5 represents a perspective view of the hook plate.

30 Referring to the drawings wherein like numerals designate like parts it can be seen that numeral 5 represents the wall of the car. In Figure 5 numeral 6 generally refers to the hook plate while numeral 7 generally refers to the detent as shown in Figure 4.

35 The hook plate consists of the T-shaped plate 8 the arms 9 of which are apertured as at 10 to receive suitable securing elements 11 whereby the plate can be secured to the wall 5 of the car. The plate 8 is provided with outstanding arms 12—12 which are apertured as at 13. The lower 40 portion of the plate 8 is bent outwardly and

upwardly to provide the hook 14 and this hook is provided with outstanding ears 15—15.

The detent 7 is in the form of an elongated arm 16 which is provided with a longitudinally extending strengthening rib 17. This arm 16 is provided with short rearwardly extending arms 18 apertured as at 19. These arms 18 interlap the arms 12 and a cotter pin 20 can be disposed through the opening 13 and 19 to swingably support the detent 7.

10 The upper portion of the arm 16 is bulged inwardly while the upper portion of the plate 8 is bulged outwardly to form the bosses 21—22 for engagement into the end convolutions of the coiled compressible spring 23 which serves to 15 maintain the outwardly curved lowered portion 24 of the arm 16 against the hook 14 and between the edges 15—15, thus preventing a check 25 from becoming displaced from the hook 14.

20 While the foregoing specification sets forth the invention in specific terms, it is to be understood that numerous changes in the shape, size and materials may be resorted to without departing from the spirit and scope of the invention as claimed hereinafter.

25 Having thus described the invention, what I claim is:—

A check holder of the character described comprising a plate formed with a hook at the lower portion thereof, a swingable detent mounted on the plate, the lower portion of the detent being engaged with the free end of the hook, and a spring interposed between the plate and the upper end portion of the detent for tensionally maintaining the lower end of the detent 35 against the hook, the end portion of said hook being provided with outwardly disposed ears between which the lower end of the detent is normally disposed.

AUGUST ZAMBORELLI. 40
